UNITED STATES PATENT OFFICE.

AXEL C. V. MALM, LEOPOLD RAUH, AND CHELSEA R. AKER, OF DAYTON, OHIO,
ASSIGNORS TO THE EGRY REGISTER COMPANY, OF DAYTON, OHIO, A COR-
PORATION OF OHIO.

MANIFOLDING DEVICE FOR TYPE-WRITING MACHINES.

1,130,751.

Specification of Letters Patent.

Patented Mar. 9, 1915.

Application filed July 20, 1914. Serial No. 852,024.

To all whom it may concern:

Be it known that we, AXEL C. V. MALM, LEOPOLD RAUH, and CHELSEA R. AKER, citizens of the United States, residing at Dayton, in the county of Montgomery and State of Ohio, have invented certain new and useful Improvements in Manifolding Devices for Type-Writing Machines, of which the following is a specification, reference being 10 had therein to the accompanying drawing.

This invention relates to manifolding devices for typewriting machines and more particularly to those parts of said devices which support the supply of paper, which 15 is usually in the form of rolls.

Various attempts have been made to provide a commercially practical device which could be attached to a typewriting machine to enable a plurality of webs of paper to be 20 passed about the platen of a typewriter and a corresponding plurality of copies secured upon each operation of the typewriter, by the use of a plurality of plies of ribbon or in any other suitable manner. Some of 25 these machines have been placed upon the market but few, if any of them, have been entirely satisfactory. One of the principal causes of the unsatisfactory character of these devices was the inability to feed the 30 paper supporting device along with the typewriter carriage without interfering with the movement of the latter. One method of feeding the paper supply is to mount the same on a carrier supported on 35 the rear part of the typewriter frame and connected with the typewriter carriage in such a manner that any movement imparted to the typewriter carriage will be transmitted to the carrier. The rolls of paper 40 are necessarily heavy and no matter how easily movable the carrier may be the inertia which must be overcome when movement is imparted to the carrier is very great. As a result the carrier when so connected with 45 the carriage imposes a drag upon the latter which seriously interferes with its operation.

The object of the present invention is to 50 overcome these difficulties and provide a paper carrier which will be caused to move along with the typewriter carriage upon each movement of the latter but which will be so connected with the carriage that it

will not impose a drag thereon or otherwise interfere with the operation thereof.

To this end it is a further object of the invention to provide a connection between the paper carrier and the typewriter carriage to cause the former to move with the latter, and to interpose in said connection 55 at some point between the paper carrier and the carriage a spring which will be compressed by the forward movement of the carriage, thereby permitting the latter to have movement relatively to the paper carrier.

A further object of the invention is to provide means for so supporting the carrier that little or no strain will be imposed upon the typewriter frame and the balance 70 of this frame will not be disturbed; and further, to provide an improved form of track for the carrier.

In the accompanying drawings, Figure 1 is an end elevation of a device embodying 75 the invention, showing the same attached to a typewriter; Fig. 2 is a top, plan view of the device shown in Fig. 1; and Fig. 3 is a sectional, detail view of the track.

In carrying out the invention we mount 80 at the rear of the typewriter a paper carrier of such a character that it will support the desired number of webs of paper. Usually these webs of paper come in the form of rolls and when in this form the carrier comprises 85 a frame in which the rolls are journaled. This carrier is mounted on the track and is arranged to move in a path substantially parallel with the line of movement of the typewriter carriage. Means are provided for 90 causing both the typewriter carriage and the paper carrier to be advanced upon each operation of the typewriting machine, to permit the typewriter carriage to have movement relatively to the paper carrier and to 95 gradually overcome the inertia of the paper carrier during this movement of the typewriter carriage relatively to the paper carrier.

In the accompanying drawings is illustrated one form of apparatus embodying this invention and carrying out the operation above described. This particular embodiment of the invention is designed for attachment to a Remington typewriter and 105 in some minor respects is particularly de-

signed for this typewriter, but it will be understood that the device can be designed for attachment to various typewriters without in any way modifying the essential features of construction. As here shown a base 5 1 is arranged in the rear of the typewriter, which is shown at 2, and is so mounted that a large portion of the weight is carried by the table 3 on which the typewriter and base are mounted. In this particular attachment the base is provided at its rear edge with depending legs 4 which rest upon the table top, and the forward part of the base rests upon the rearwardly projecting 10 base of the typewriter. This forward edge of the frame is recessed, as shown at 5, to extend partially about the upright members of the frame and thus accurately position the base with respect to the frame. Attaching devices 6 are provided to retain the base in engagement with the said frame members.

Mounted upon the base 1 is a paper carrier designed to support a plurality of webs 25 of paper. As has been stated, these webs of paper usually come in the form of rolls and in this particular embodiment of the invention, four webs are utilized. The carrier is, therefore, shown in the form of a 30 frame comprising vertical end members 7 connected one to the other by tie rods 8 and having at their lower ends trucks 9 adapted to travel on the base 1. Preferably, the base 1 has a track or tracks to coöperate 35 with the trucks of the carrier. In the present instance these tracks comprise parallel bars 10 rigidly secured to the base, spaced some distance apart and provided on their inner faces with V-shaped grooves 11. The 40 trucks 9 of the carriage comprise similar parallel bars which are provided on their outer faces with V-shaped grooves 12 corresponding in size with the grooves 11 of the track. The distance between the outer 45 edges of the truck members 9 is such that they will fit snugly between the track members and when supported at the proper height the grooves of the truck members and of the track members will register. 50 Mounted in the race-way formed by the grooves of the two members are hardened steel balls 13. Any suitable number and arrangement of balls may be used but it is preferable to use a small number of balls 55 and to space the same apart by spacing members or rods 14. As here shown a single ball is placed at each end of the track and a group of balls near the center of the track, the group of balls being spaced away from 60 the end balls, respectively, by spacing rods 14. These spacing rods are cylindrical in shape and are of the same diameter as the balls. Consequently, they will engage the walls of the race-way and will exert a small 65 amount of friction thereon. This slight re-

sistance to the movement of the carrier is desirable as it enables the same to be more readily controlled and it is not sufficient to interfere with the movement of the carrier. Further, this construction of track provides 70 a very steady, non-vibratory support for the carrier. The balls and rods fit snugly in the race-ways to prevent any appreciable movement of the trucks relatively to the tracks, excepting only the straight longitudinal movement. It will be understood that while this particular form of track has been shown for supporting the carrier this is chosen merely because it is very satisfactory in operation and the other features 80 of the invention can be utilized in connection with a track or guideway of any suitable character.

Rolls of paper, which are shown at 15, may be mounted in the frame of the carrier in any suitable manner but, as here shown, they are carried by rods 16 extending through the respective rolls and mounted at their ends in the frame members 7. The webs of paper are drawn from the rolls 90 about suitable guides which may be formed by the tie rods 8 and carried to the typewriter where they are passed about the platen 19, which is mounted on the carriage 20, and properly interleaved with the several plies of inking ribbon or other transfer material. It will be noted that the line of movement of the paper carrier is parallel with the line of movement of the typewriter carriage and because of the manner of 100 mounting the carrier it is very easily moved in spite of the weight of the four rolls of paper.

In order to advance the paper carrier along with the typewriter carriage there is 105 shown, in the present embodiment of the invention, a connecting member connected at its ends with the paper carrier and typewriter carriage, respectively. Interposed in the connection between the typewriter carriage and the paper carrier is a spring which is so arranged that it will be compressed by the first part of the movement of the typewriter carriage, thus permitting the typewriter carriage to have movement relatively to the paper carrier. As the spring is placed under tension by the movement of the carriage the inertia of the paper carrier is gradually overcome and movement imparted to the carrier. After the movement 110 of the carriage has been completed the expansion of the spring will complete the movement of the carrier so that the same is always maintained in a proper position relative to the carriage. When the typewriter 115 is being operated at a normal rate of speed the successive movements of the carriage take place before the expansion of the spring is completed. Consequently, after the movement of the paper carrier has begun it is 120 125 130

caused to move forward continuously so long as the typewriter is operated at a normal rate of speed. As a result very little resistance is offered to the movement of the typewriter carriage and this resistance in no way interferes with the normal operation of the carriage. This connection between the paper carrier and the carriage may be in various forms but that employed in the present embodiment of the invention comprises a bar 21 connected at its ends with the carriage and with the paper carrier, one of these connections being slidably, and a spring being interposed between the bar and that member with which it is slidably connected. As shown, the bar is pivotally connected at one end to the central portion of the frame member 7, as shown at 22, and is slidably mounted at its other end upon a pin 23 mounted upon the typewriter carriage and extending longitudinally thereof, and a spring 24 is coiled about the pin between its head and the bar, the bar being arranged, in the present instance, on the right hand side of the machine as the operator faces it. The bar is preferably slotted to receive the pin 23 and this loose connection permits of pivotal and sliding movements of the bar transversely of the pin, as well as longitudinally thereof. It will be apparent that as the typewriter carriage moves to the left in Fig. 2 it will move away from the bar 21, causing this bar to compress the spring 24 against the head of the pin and as the tension of the spring increases it will overcome the inertia of the paper carrier and start the same in motion. In the case of a single operation of the typewriting machine the carriage will come to a stop before the carrier has completed its movement and this movement will be completed by the inertia which the carrier has acquired, aided by the expansion of the spring. However, in the normal operation of the typewriter the movements of the carriage follow one another so rapidly that there is very little expansion of the spring between the movements and, consequently, the carrier is caused to move forward continuously. After having been once started in motion it is carried along by its inertia and the spring with very little drag upon the typewriter carriage and this drag is never sufficient to interfere with the movement of the carriage or to prevent the proper spacing of the letters as the keys are struck.

The operation of the device will be readily understood from the foregoing description of the several parts thereof and it will be apparent that a very simple, inexpensive device has been produced for causing the paper carrier to be advanced along with the typewriter carriage without in any way interfering with the operation of the carriage; and further, that the carrier is so mounted

that it will not impose any material weight upon the typewriter frame and that it will be very easily moved from one position to another, but always maintained in perfect balance.

While one embodiment of the invention has been shown and described it will be understood that this has been chosen for the purpose of illustration only and that the invention is not limited to the details of construction so shown and described, for obvious modifications will occur to one skilled in the art.

Having thus fully described the invention what is claimed as new and desired to secure by Letters Patent, is:—

1. The combination, with a typewriting machine having a carriage, of a paper carrier supported adjacent to said machine, and a connection between said carriage and said paper carrier, whereby the movement of the former will impart movement to the latter, said connection being such as to permit said carriage to have movement relatively to said paper carrier during the normal operation of said parts.

2. The combination, with a typewriting machine having a carriage, of a paper carrier, supported adjacent to said machine, and a connection between said carriage and said paper carrier constructed and arranged to yield during the normal movement of said carriage.

3. The combination, with a typewriting machine having a carriage, of a paper carrier supported adjacent to said machine, and a connection between said carriage and said paper carrier comprising a spring arranged to be placed under tension by the normal movement of said carriage.

4. The combination, with a typewriting machine having a carriage, of a paper carrier supported adjacent to said machine, a connection between said carriage and said paper carrier comprising a connecting member, and a spring interposed between said connecting member and one of said parts to be connected.

5. The combination, with a typewriting machine having a carriage, of a paper carrier supported adjacent to said machine, a connection between said carriage and said paper carrier comprising a bar slidably connected with one of said parts to be connected, and a spring interposed between said bar and said part to be connected.

6. The combination, with a typewriting machine having a carriage, of a paper carrier supported adjacent to said machine, a connection between said carriage and said paper carrier comprising a bar slidably connected with said carriage, and a spring interposed between said bar and said carriage.

7. The combination, with a typewriting machine having a carriage, of a paper car-

rier supported in the rear of said machine and movable in a line parallel with the line of movement of said carriage, a bar connected at one end to said carriage, a pin 5 mounted on said carriage, extending loosely through said bar and having a head, and a spring confined between said bar and the head of said pin.

8. The combination, with a typewriting 10 machine having a carriage, and a paper carrier supported adjacent to said machine, of means to cause the movement of said carriage to gradually overcome the inertia of said paper carrier and cause said carrier to 15 move along with said carriage.

9. The combination, with a typewriting 20 machine comprising a frame and having a carriage, of a base arranged in the rear of said typewriting machine and having one edge supported by said frame and provided with means to position said base relatively to said frame, devices to support the other edge of said base independently of said

frame, a paper carrier movably mounted on said base, and a connection between said 25 paper carrier and said carriage.

10. The combination, with a typewriting machine comprising a frame and having a carriage, of a base arranged in the rear of said typewriting machine and having one 30 edge supported by said frame, devices to support the other edge of said base independently of said frame, a paper carrier movably mounted on said base, and a connection between said paper carrier and said 35 carriage comprising a spring arranged to yield during the normal movement of said carriage.

In testimony whereof, we affix our signatures in presence of two witnesses.
